United States Patent Office.

W. GARRISON AND CHARLES H. STEVENS, OF SYRACUSE, NEW YORK.

Letters Patent No. 89,573, dated May 4, 1869; antedated December 8, 1868.

IMPROVED HOLDBACK

The Schedule referred to in these Letters Patent and making part of the same.

To all whom it may concern:

Be it known that we, W. GARRISON and CHARLES H. STEVENS, of Syracuse, in the county of Onondaga, and State of New York, have invented a new and useful Improvement in Holdback; and we do hereby declare that the following is a full, clear, and exact description thereof, which will enable those skilled in the art to make and use the same, reference being had to the accompanying drawings forming part of this specification, in which—

Figure 1 is a sectional view, showing the parts detached.

Figure 2 is a sectional view, showing the parts engaged.

Figure 3 is a top view of the thill-iron; and

Figure 4 is a bottom view of the same.

Figure 5 is a front view of the hook.

Similar letters of reference indicate corresponding parts in all the figures.

The thill-iron A is fastened to the thill B by means of screws, as shown in fig. 2, and connection is made between the iron A and a hook, C, on the end of the breeching-strap D, in a general manner, the same as ordinarily.

In the elevated portion of the thill-iron is cast a T-shaped opening, E, figs. 1 and 2, and it is also provided with a swinging platform, f, which is supported by being pivoted at one end to A, while the other end is supported by a spiral spring, g, fig. 2.

The hook C is formed by a flat head, having a pair of ears c c, fig. 5.

To engage the parts, the hook C is brought into position, (shown in fig. 1,) and its head is then introduced, through the T-shaped opening, into the thill-iron A, until the ears c have passed the curved corners k k of said thill-iron.

The hook is then thrown over into the position shown in fig. 2, and the ears c become engaged with

the retaining corners k, and the shoulders m of the hook also engage with the parts n of the thill-iron, and thus the hook is secure in its connection until it is thrown over forward again, as shown in fig. 1.

To prevent the hook from being turned over into the disengaging position too easily, it is provided with a flat face, h, against which the spring-platform f is pressed. But in case the whiffle-tree breaks, or a like accident occurs, the hook C is thrown over as soon as a forward strain is brought upon it, and then the hook pulls out, or disengages readily, so that the horse is freed from the carriage or vehicle.

The spring-platform causes the ears c c to engage with the retaining corners k k, and also prevents all rattle of the parts.

The thill-iron A is made of cast malleable metal, and has a pair of lugs i i, fig. 4, cast upon it in such manner that by bending them over the pivot of the swinging platform f it is thereby held in place in a simple and cheap manner.

All the fitting necessary to put the parts together after they are cast is to secure the platform f to the iron, or shell A, by bending down the lugs i i.

By these means we obtain a holdback connection which is cheap, handy, and reliable.

We do not claim a recessed thill-iron and hook, as in patent No. 36,347; but

What we do claim, and desire to secure by Letters Patent, is—

The swinging platform f and spring g, in combination with a flat-headed hook C h and thill-iron A, as and for the purpose herein shown and described.

W. GARRISON.
CHAS. H. STEVENS.
